No. 712,255.

Patented Oct. 28, 1902.

D. O. BRUNNER.

RAIL JOINT.

(Application filed May 18, 1902.)

(No Model.)

UNITED STATES PATENT OFFICE.

DANTON O. BRUNNER, OF SOMERSET, OHIO.

RAIL-JOINT.

SPECIFICATION forming part of Letters Patent No. 712,255, dated October 28, 1902.

Application filed May 13, 1902. Serial No. 107,073. (No model.)

To all whom it may concern:

Be it known that I, DANTON O. BRUNNER, a citizen of the United States, and a resident of Somerset, in the county of Perry and State of Ohio, have invented new and useful Improvements in Rail-Joints, of which the following is a full, clear, and exact description.

My invention relates to improvements in rail-joints; and the object that I have in view 10 is the provision of improved means for protecting the meeting or adjacent ends of two rails from the pounding or "hammering" action of the wheels of passing cars, thereby contributing to the easy and smooth running 15 of trains, reducing the tendency of the parts to work loose, and minimizing abrasion and wear of the joint.

A further object of the invention is the provision of an improved form of rail-chair 20 designed to couple the ends of adjacent rails in such a way as to dispense with the use of ordinary angle-bars and bolts, whereby the track can be laid more expeditiously and the cost of maintenance is reduced, owing to the 25 fact that the time of the track-repair gang is not consumed so largely in inspecting the joints and tightening the nuts on the bolts.

With these ends in view the invention consists of a rail-joint embodying novel features of construction and arrangement of parts, which will be hereinafter fully described and claimed.

Reference is to be had to the accompanying drawings, forming a part of this specification, 35 in which similar characters of reference indicate corresponding parts in all the figures.

Figure 1 is a plan view of a rail-joint embodying my invention and with certain of the parts broken away. Fig. 2 is a vertical cross-section taken in the plane indicated by the dotted line 2 2 of Fig. 1. Figs. 3 and 4 are views in side elevation and plan, respectively, of an end portion of a rail adapted for use in connection with the improved chair. Fig. 5 40 is a vertical cross-section through the improved rail-joint, illustrating a slightly-modified form of the chair, the plane of section through the chair being indicated by the dotted line 5 5 of Fig. 6; and Fig. 6 is a detail perspective view of a chair embodying 45 my improvements and shown in its applied position by Fig. 5.

The improved chair of the present invention consists of a plate 5, an upstanding web 6, and a foot-flange 7, all of which are made 55 of a single piece of metal in any usual or preferred way—as, for example, by casting the chair. The plate 5 of the chair should be made of sufficient length to span a series of ties, and, as shown by Fig. 1, this plate is 60 adapted to rest upon three of the ties, (indicated at a;) but it will be understood that the length of the plate is not material. The flange 7 extends lengthwise along one edge of the plate 5, and this flange is arranged to 65 extend upwardly a suitable distance from the rail-engaging face 5^a of said plate, the inner edge of the flange 7 being undercut to form a groove 8^a, whereby the flange is adapted to overhang said rail-engaging face of the 70 base-plate, as shown more clearly by Figs. 2, 5, and 6 of the drawings. The web 6 extends in a vertical direction from the upper face of the plate 5, and this web should be made of sufficient length to extend longitudinally of 75 the plate, although this specific length of the web is not a material part of the invention. The web is preferably made tapering in cross-section in order that it may have engagement 80 laterally with the foot and head of the rail-way-rail, and this tapered form is given to the web by making the inner face 6^a at an angle to the outer exposed face 6^b, said inner face 6^a being inclined in an upward direction away from the rail-engaging face 5^a 85 and the outer exposed face 6^b of the web, as shown more clearly by Figs. 2, 5, and 6. The web should be high enough to lie substantially flush with the top active edge of the rail-head; but it is not necessary that this 90 top edge of the web throughout the length thereof should be in flush relation to the corresponding edges of the meeting rails. It is sufficient to have the middle portion of the web at the top thereof lie in flush relation to the top edges of the rails, and I therefore prefer to make the end portions of the web inclined or curved, as indicated at 95 8, thus bringing the end portions of the web below the plane of the middle portion thereof 100 along its top edge, as more clearly represented by Fig. 6. The highest part of the web is at the middle thereof, so that the web may span the joint between the meeting rails, and this

high part preferably extends a short distance on opposite sides of the joint, while the receding portions 8 of the web are adapted to lie slightly below the top faces of the rails, 5 thus giving a good approach for the wheels on the web when said rails pass over the joint. The outer edge of the base-plate 5 projects beyond the web 6, and in this extended edge portion of said base-plate is 10 formed a series of spike-openings 9. The other flanged edge 7 of the base-plate is also provided with a series of spike-openings 10, the latter extending through a portion of the upstanding flange 7. The base-plate is 15 adapted to be placed firmly upon the series of ties *a*, and suitable spikes 11 can be driven through this plate in order to firmly fasten the chair upon the ties.

One of the important features of my invention consists in the provision of means whereby the rails may have interlocking engagement with the chair, and these parts are held together preferably without the employment of bolts and angle-irons. In embodying this part of my invention in the chair I provide it with the locking-lugs 12 12^a, the same being of angular form in cross-section and disposed at suitable intervals from each other on the inner inclined face 6^a of the upstanding web 6. These locking-lugs rise from the rail-engaging face 5^a of the chair, and they have vertical inner edges, as represented by Figs. 2, 5, and 6. The rail to be used in connection with the improved chair, 30 is represented by Figs. 2, 3, 4, and 5, and is indicated by *b*. The foot *b'* of this rail is provided with a notch or notches 13, and, as shown by Fig. 4, I prefer to provide a notch 13 in each side edge of the rail-foot. It will 35 be understood that the rail may be provided with one notch in one side edge of its foot; but for convenience in laying the rails I prefer to employ the notches in both side edges, thus enabling the rail to be brought either 40 end to toward the joint and properly engage with the chair.

In the construction of the chair shown by Figs. 5 and 6 the upstanding web 6 is provided with a transverse and longitudinal recess 14 and with a slot 15 along its lower portion, said slot arranged to expose an edge portion of the rail-foot when the rail is properly seated in the chair. This construction of the web enables me to place certain of the spike- 50 openings 9 in the vertical plane of the web 6, and the spikes can be driven through this part of the plate 5 in a manner for the heads to engage with the foot-flange of the rails on one side thereof.

60 In laying the track the chair is placed on the ties *a*, and it is fastened thereto by driving the spikes through the holes 10 and through some or all the holes 9. The rail is now brought to the chair, and it is canted or 65 tilted to an inclined position in order that one side edge thereof may slip into the groove 8^a of the overhanging flange 7, the notch 13

in the rail being placed in alignment with one of the lugs 12, after which the rail is dropped into place in a manner for the lug 12 70 to enter the notch 13. This arrangement brings the opposite edge portions of the foot of the rail into engagement with the grooved edge of the overhanging flange 7 and the lower part of the inclined face 6^a on the upstanding web 6, while the head of the rail abuts against the upper part of the inclined face 6^a of said web. The other rail is now brought to the chair and is placed in position in the same way, so that it will engage with the other 80 lug 12^a and with the flange 7 and the web 6. The upper face of the web 6 extends across the meeting-line between the two rails, and the high part of this web is disposed in flush relation to the meeting ends of the rails, as 85 shown by Fig. 5, whereas the end portions of the web lie slightly below the heads of said adjacent rails, as shown by Fig. 2. The rails are kept in their proper places by engaging with the flange and the web of the chair, and 90 the endwise displacement of the rails is prevented because they have interlocking engagement with the chair, owing to the lugs 12 12^a fitting in the notches 13 of said rails. In practice I prefer to make the locking-lugs 12 95 of less width than the length of the notches 13, as shown by the broken-away portion of the chair in Fig. 1, and this construction allows the rails to have the necessary expansion and contraction due to atmospheric 100 changes. If a chair of the style shown by Figs. 5 and 6 is employed, the rail has a portion of its foot exposed through the slot 15 and the recess 14 of the vertical web, and this allows one or more spikes to be driven through 105 certain of the holes 9, so as to engage with the rail, thereby contributing to the security of the rail-fastening.

If preferred, the top part of the upstanding web (shown by Figs. 5 and 6) may be reinforced by the provision of a rib 16 on the outer recessed face 14, said rib extending longitudinally along the middle portion of the web and compensating for any weakening of the web due to the formation of the recess 110 and the slot thereon. The employment of the upstanding web having the peculiar relation heretofore described to the meeting edges of the rails is an important feature of the present invention, because this web is 115 made to sustain a part of the weight of the train when passing over a joint, and the action of the wheels on the rails at the meeting-line thereof is minimized, thus overcoming 120 the pounding or hammering effect of the 125 wheels on the ends of the rails, reducing abrasion or mutilation of said ends of the rails, and contributing to the ease and smoothness of the passage of the train at the rail-joints.

Having thus described my invention, I claim as new and desire to secure by Letters Patent—

1. A rail-joint chair comprising a tie-plate,

and an upstanding web having a wheel-bearing top edge, said web provided with a longitudinal slot or recess, the edge of which slopes inwardly toward the inner face of the web, and said tie-plate having spike-openings which are exposed through the slotted web.

5. A rail-joint chair comprising a tie-plate, and a longitudinally-recessed web having a wheel-bearing top edge, said tie-plate being provided with spike-openings which are exposed by said recess of the web.

10. A rail-joint chair provided with an upstanding web having a wheel-bearing face, said web being also provided with a longitudinal slot adapted to expose the foot of a rail seated in the chair.

15. In a rail-joint chair, the combination of

a chair provided with locking projections, notched rails seated on the chair and having direct interlocking engagement with said projections, a bearing-flange engaging with one edge of the rail-feet, and an upstanding web engaging with the other side edges of the rails along the feet and heads thereof, said web having its top edge disposed in flush relation to a part of the heads of the rails.

20. In testimony whereof I have signed my name to this specification in the presence of two subscribing witnesses.

DANTON O. BRUNNER.

Witnesses:

W. F. GORDON,

W. J. KRUNLAUF.
